ATTORNEY

UNITED STATES PATENT OFFICE

158,111

PACKAGING CONTAINER OR SIMILAR ARTICLE

James C. Madden, 3rd, New York, N. Y., assignor to Consolidated Lithographing Corporation,
New York, N. Y., a corporation of New York

Application November 3, 1947, Serial No. 142,282

Term of patent 3½ years

(Cl. D58—12.6)

To all whom it may concern:

Be it known that I, James C. Madden, 3rd, a citizen of the United States of America, residing in the city, county, and State of New York, have invented a new, original, and ornamental Design for a Packaging Container or Similar Article, of which the following is a specification, reference being had to the accompanying drawing, forming a part thereof.

Fig. 1 is a perspective view of a packaging container, showing my new design;

Fig. 2 is a side view thereof; and

Fig. 3 is a top plan view thereof.

I claim:

The ornamental design for a packaging container or similar article, as shown.

JAMES C. MADDEN, 3RD.
